UNITED STATES PATENT OFFICE.

FISHER R. CLARKE, OF STOCKTON, CALIFORNIA.

MAIL-BAG.

1,125,006.

Specification of Letters Patent.

Patented Jan. 12, 1915.

Application filed February 16, 1914. Serial No. 818,906.

To all whom it may concern:

Be it known that I, FISHER R. CLARKE, a citizen of the United States, residing at Stockton, in the county of San Joaquin and State of California, have invented new and useful Improvements in Mail-Bags, of which the following is a specification.

This invention relates to improvements in mail bags.

10 One of the objects of my invention is to provide a simple, substantial and durable mail bag, which is so constructed that the upper end of same may be made shorter and folded in such a manner that the opening is considerably contracted without decreasing the capacity of the bag.

Another object of the invention is to provide a means for closing the contracted folded opening of the bag, and to provide 20 means for drawing the sides and closure tightly together.

Further objects will hereinafter appear.

The invention consists of the parts and the construction and combination of parts as 25 hereinafter more fully described and claimed, having reference to the accompanying drawings, in which—

Figure 1 is a perspective view of the upper end of the bag showing it in the open 30 position. Fig. 2 is a rear view of the upper end of the bag in perspective. Fig. 3 is a cross section of the upper end of the bag. Fig. 4 is a front view of the bag.

Referring to the drawings, A indicates 35 the bag proper, which is constructed in most cases of heavy canvas. The upper open end of the bag is reinforced on two opposite sides, and is creased at an angle with relation to the straight sides of the bag on lines 40 2, 3 and 4 to form V-shaped sections 5 and 6 which are adapted to fold inwardly and downwardly in the direction of arrow a when the bag is closed. This construction insures the mouth being much shorter than 45 the width of the main portion, less fastenings and a safer and more rigid structure.

Suitably secured to the upper front edge of the bag is a reinforcing leather strip 7, the ends of which project partly beyond the 50 folding edge or crease 4, as indicated at 8. Similarly secured to the rear side of the bag and being sufficiently wide to project a little beyond the fold or crease 2 is a flap member 9, to which is secured, as at 10, a pair of 55 curved locking bolts 11. Suitably secured to the interior surface of the rear side of the

bag and below the mouth is a pair of locks 12 having cylindrical extensions 13 formed thereon and socket portions 14 formed interiorly thereof through which the curved locking bolts 11 are adapted to pass.

The folded sections 5 and 6, on each side of the bag, are provided with eyelets 15 and 16, the interior diameters of which are sufficiently large to pass over the cylindrical extensions 13 formed on the locks. The front edge of the bag, to which the reinforcing strip 7 is secured, is similarly provided with eyelets which are also adapted to pass over the cylindrical extensions or keepers 13. 65 The several foldable sections, together with the front face of the bag can thus be folded over the keepers 13 and locked in this position by the bolts 11. The upper end of the bag will thus be considerably contracted, 70 when folded and when locked in this position will also be completely covered by the flap 9.

The curved lock bolts will cause the folds of the bag and flap to be drawn tightly together, as indicated in Fig. 3, when the bolts are thrown over into locking position with relation to the keepers 13; this being caused by the cam action which is produced by the keeper and curved bolts. The tight closure 80 formed in this manner will positively prevent admission to the bag when this is locked, and the overlapping of the projecting ends formed on the flap and reinforcing strip 7 will protect the folds of the bag and 85 guard these against unnecessary wear.

The particular construction of the locks does not form any part of the present invention. These locks may be snap locks and in order to lock the bag it is only necessary to 90 pass the bolts into the sockets 14 of the keepers. The bag can only be opened by authorized persons having possession of the proper key which is inserted through a key plate 18 secured to the side of the bag, as 95 at 19.

The bolts may be considerably reinforced by forming them of T cross sections, as indicated at 11^a, and the sockets 14 may be of similar shape to produce the greatest 100 strength possible without interfering with the cam action in closing, and the securing flange 20 of same, together with the base of the lock, indicated at 17, may be flattened and reduced as much as possible to permit a 105 compact and tight closure of the bag. The advantages of this construction, are first, by

making the bag mouth much shorter than the width of the bag, the number of fastenings may be reduced and brought nearer together. The mouth can be made more rigid 5 and less liable to be distorted or twisted so as to release the locks. The eyelets so placed in the angular V-shaped folds and the front of the bag, that they will register automatically when closed, insure the rapid and accurate closing. By the angular inward direction of the folds the eyelets and the locks 10 may be placed at such a distance below the mouth as to increase the security of the fastening and allow the bag mouth to be closely drawn together by the overlapping flap, 15 which result in increased by the cam or drawing action of the hook shaped bolts as they enter and engage the receiving sockets.

The above construction while contracting 20 the mouth of the bag into a conical compact form, leaves the whole lower portion of the full size and capacity with little or no reduction, and a very great increase in the rapidity of handling. When the bag is hung 25 up by the suspending rings to be filled it presents a wide rectangular opening to receive letters and objects thrown from a distance in the usual manner.

Having thus described my invention, what 30 I claim and desire to secure by Letters Patent is—

1. A bag mouth having parallel reinforced 35 sides of less length than the width of the bag and intermediate inwardly foldable V-shaped end portions, diverging from the ends of the side portion to the wider portion of the bag, coacting eyelets, and lock extensions, and bolts fixed to the rear flap and adapted to enter the lock extensions, 40 said bolts and lock extension sockets being curved on a radius of movement of the closing flap and of T form in cross section.

2. A mail bag consisting of a body having 45 a mouth, a flap for closing the mouth connected to the back of the body and having a free part foldable over the front of the body,

locks secured to the back of the mouth and having substantially cylindrical extensions provided with sockets which are curved outwardly and upwardly at the front ends 50 thereof to provide cam faces, locking bolts having similar cam faces borne by the free part of the flap, the front part of the mouth having eyelets which are adapted to receive the lock extensions and to also receive the 55 bolts to enable the latter to enter the sockets and engage the cam faces thereof so as to draw the free part of the flap downwardly and over the mouth.

3. A mail bag consisting of a body having 60 a mouth, a flap for closing the mouth connected to the back of the body and having a free part foldable over the front of the body, locks having extensions formed with sockets 65 secured to the back of the mouth, the front part of the mouth having eyelets adapted to receive the lock extensions, and locking bolts on the free part of the flap adapted to pass through the eyelets and to enter the sockets of the lock extensions.

4. A mail bag consisting of a body having 70 a mouth, a flap for closing the mouth connected to the back of the body and having a free part foldable over the front of the body, locks having extensions formed with sockets 75 secured to the back of the mouth, the front part of the mouth having eyelets adapted to receive the lock extensions, locking bolts on the free part of the flaps adapted to pass through the eyelets and to enter the sockets 80 of the lock extensions, and means whereby when the bolts enter the sockets the free part of the flap will be drawn downwardly over the mouth of the bag.

In testimony whereof I have hereunto set 85 my hand in the presence of two subscribing witnesses.

FISHER R. CLARKE.
